UNITED STATES PATENT OFFICE.

WALTER S. MOODY, OF SCHENECTADY, NEW YORK, ASSIGNOR TO GENERAL ELECTRIC COMPANY, A CORPORATION OF NEW YORK.

TRANSFORMER.

No. 840,150.

Specification of Letters Patent.

Patented Jan. 1, 1907.

Application filed December 16, 1901. Serial No. 86,030.

To all whom it may concern:

Be it known that I, WALTER S. Moody, a citizen of the United States, residing at Schenectady, county of Schenectady, State of New York, have invented certain new and useful Improvements in Transformers, of which the following is a specification.

This invention relates to improvements in transformers of the so-called "core" type, the cores of which constitute a single magnetic circuit.

The object of the invention is to provide for automatic regulation under varying conditions of load, to obtain a transformer with windings adapted for interchangeable connection on different-supplied voltages, and to facilitate the mechanical construction of the transformer.

A serious difficulty which is always encountered in transformers of this class when they are required to supply more than one voltage, and especially when used in connection with three-wire circuits, is that of obtaining automatic regulation. The simplest transformer of this class has its two windings subdivided, the resulting parts being mounted on the respective core-legs, so that half of each winding is located on each leg. When from between the two parts of the secondary

winding of such a transformer a connection is taken to the neutral of a three-wire system, the loads on the sides of which are frequently varied with respect to each other, it happens that the voltage of the more heavily loaded part of the secondary decreases, while the voltage of the less heavily loaded part increases, this condition being the reverse of that desired. This result is due to the fact that the increased secondary ampere-turns caused by overloading oppose in an increased degree the ampere-turns of the part of the primary on the same leg of the core, so that there is established an opposition to the magnetization of the other core-leg. This opposition of magneto-motive forces causes the establishment of consequent poles in the end pieces of the core which connect the core-legs to complete the magnetic circuit, and a part of the flux which ought to pass through the leg carrying the more heavily loaded secondary is shunted as leakage from pole to pole across the air-space between the legs. This occurs in a very high degree when, as is

customary, the transformer is incased in an iron box, which of course provides a ready path for the leakage flux. Therefore since the core-leg on which the more heavily-loaded secondary is mounted carries a smaller flux than the other leg the secondary coils on the former leg have a smaller induced voltage per turn than the coils on the latter leg, and the counter-electromotive force of the part of the primary on the more heavily loaded side will therefore be reduced. It should be noted at this point that no flux is shunted from the core on which the lightly-loaded secondary is mounted. Now it is clear that the generator will supply more current when the voltage of the primary on the loaded side drops, with the result that the whole core magnetization is increased, which causes increased voltage on the primary and secondary on the unloaded side of the system. Since the sum of the voltages on the two parts of the primary must be substantially equal to the impressed voltage, which is constant, it follows that all the coils on the loaded leg of the core have less than the normal voltage, while those on the unloaded leg have a voltage higher than the normal, which is the reverse of the required conditions, as above stated.

In Patent No. 595,403, issued to me on December 14, 1897, is disclosed an arrangement of the secondary coils whereby the above-described difficulty is overcome by subdividing the part of the secondary on each leg into two parts and connecting parts of the secondary on both core-legs across the respective sides of the three-wire system. The present invention is another embodiment of the same generic idea—namely, that no matter how much more heavily loaded one side of the three-wire system may be with this arrangement of secondary coils the total demagnetizing effect of the secondary coils will always act equally on each leg of the core and there will be no tendency to unbalance the flux. The specific disclosure in said patent shows the secondary divided into four parts instead of two, as before, and each part on one core-leg is connected in series with a part on the other core-leg, the pairs being connected across the respective sides of the three-wire system. I have found that the parts of the secondary coils of the different

legs can be connected in multiple across one side of a three-wire system without interfering with the good automatic regulation obtained by connecting two coils on different legs across one side of the system, as shown in my patent above noted. By thus connecting the coils in multiple an important advantage is gained in that the coils on the same core-leg or on different core-legs can be changed from a series connection to vary the potential either on a three-wire circuit or on a two-wire circuit of double voltage.

Of the drawings, Figure 1 is an elevation of a transformer of the core type, showing the primary and secondary windings mounted on the two parallel core-legs. Fig. 2 is a plan of the same, showing the concentric arrangement of the primary and secondary coils and the connections of the primary. Fig. 3 is an elevation of the same transformer, showing the primary coils in dotted lines to disclose the secondary coils. Fig. 4 is a plan of the same, showing the connections of the secondary winding entering the connection-board B. Fig. 5 is a partial view of the transformer casing, showing the secondary connections of Fig. 4 extending out of the casing. Fig. 6 is an elevation of the single-circuit core without the primary winding and showing in section the inner and outer coils IS and OS of the secondary winding mounted on the parallel core-legs, the two parts of the winding on the same leg being connected in multiple with each other for the lowest voltage. Fig. 7 is an elevation of the transformer without the primary winding, showing the outside secondary wound with tape T, the coils being connected in series for the next higher voltage. Fig. 8 is a view in which the coils constituting a pair or set, one on one leg and one on the other, are connected in multiple across one side of a three-wire circuit. Fig. 9 is a partial view of a transformer-casing, showing the secondary leads emerging from the casing, as in Figs. 4 and 5, and connected, as in Fig. 8. Fig. 10 is a partial view of the casing, showing secondary leads emerging from the casing, which leads are connected in a slightly-different manner from Fig. 8 to obtain a multiple connection of the coils on the different legs; and Figs. 11 and 12 are diagrams showing the connections of the leads in Figs. 9 and 10, respectively, to the secondaries of the transformers.

It is preferable, although not necessary, that the primary winding should be mounted outside the secondary, as shown in Figs. 1 and 2, in order to obviate the necessity of insulating both sides of the high-potential winding from the other winding and from the core. It is highly desirable also in this type of transformer that the high and low potential windings should be mounted concentrically with respect to each other, as

shown in Figs. 2 and 3. The primary winding may be composed, as shown, of a number of separately-wound coils P, connected in series. The windings are usually mounted on the legs of the core O in the positions shown. This has been found to be the best arrangement; but the invention is not limited to this, as the coils may be mounted in other ways. The core is preferably constructed with a cruciform cross-section, as indicated in Figs. 2 and 4, and is preferably built up of steel sheets in any manner suitable for completing the magnetic circuit. The leads P^a P^x of the separate primary coils connected in series on one leg and the leads P^b P^y of the separate primary coils connected in series on the other leg are suitably arranged, as shown in Figs. 1 and 2, so that all the coils on one leg can be connected in series or multiple with the coils on the other leg to adapt them to different impressed voltages. I have found that this variation of the series and multiple relations of these sets of coils does not affect the automatic regulation attained as a result of the arrangement of the secondary coils in accordance with the present invention, as in any event in case one side of the three-wire system is more heavily loaded than the other the disposition of the loaded secondary on both legs of the core prevents any opposition of magnetizing forces, which would result in the formation of consequent poles and a shunt flux of leakage.

As shown in Figs. 2 and 4, the secondary winding S is divided into four coils, two of which are mounted on each core-leg, the outer coils OS being concentric with the inner coils IS and all of them extending the entire length of the core-legs. As shown in Fig. 3, the leads of all the coils are brought up to the top of the apparatus. In this figure S^3 and S^4 are the start and finish of the left-hand inner coil IS, S' and S^2 are the start and finish of the left-hand outer coil OS, S^5 and S^6 are the start and finish of the right-hand outer coil OS, and S^7 S^8 are the start and finish of the right-hand inner coil IS. As shown in Fig. 4, these leads are carried through a connection-board B so as to be brought out of the transformer-casing C of Fig. 5 in the order indicated in the latter figure.

In Figs. 6 and 8 the primary winding is not shown in order that the arrangement of the secondary coils may be more readily understood. In Fig. 6 the four coils of the secondary winding are shown in section, being separated from the core O by the insulation I' , from each other by the insulation I^2 , and from the primary coils by insulation which is composed in part of the tape T of Fig. 7.

An important mechanical advantage in providing two secondary coils in multiple on each leg is the opportunity it offers of wind-

ing a transformer for a very large current output without using heavy conductors, the objection to heavy conductors being of course the difficulty of bending them into 5 coils of small diameter. The multiple coils can carry heavy loads which a single coil could not, unless it were so heavy that the core would be twisted in the process of winding conductors upon it. The conductors are usually wound in a sheet of four wires, so that if the wires are very large the core is subjected to great strains in winding. An important electrical result in providing 10 two secondary coils on each leg is that the transformer can supply current of three different voltages. In Fig. 6 the two coils on each leg are connected in multiple with each other to supply, for example, one hundred and fifteen volts. In Fig. 7 the coils on one 15 leg are in multiple with each other, and each is in series with one of the coils on the other leg to supply twice said voltage or two hundred and thirty volts. The most important result to be obtained by the use of the invention, however, is shown in Fig. 8, where one 20 coil on one leg is in multiple with a coil on the other leg across one side of a three-wire system and the other coil on the first leg is in multiple with the other coil on the second leg across the other side of the three-wire system. The set of coils having the leads S' 25 and S² S³ is connected across one branch of the three-wire circuit, and the set of coils having the leads S⁴ S⁵ and S⁶ S⁷ is connected 30 across the other branch of the three-wire circuit, the coils of each of these sets being connected in multiple, one in each set being located on one leg of the core and the other of said set being located on the other leg of 35 the core.

In Figs. 9 and 11 is shown the method of connecting the leads extending outside the casing, as shown in Fig. 5, in accordance with the arrangement shown in Fig. 8. 40 Leads S⁴, S⁶, S², and S⁸, which are the finishing-leads of the respective four coils, are all connected with the neutral N. The starting-lead S³ of the left-hand inside coil and the starting-lead S⁵ of the right-hand outside 45 coil are both connected to one outside line of the three-wire circuit, and the starting-lead S' of the left-hand outside coil and the starting-lead S⁷ of the left-hand inside coil are both connected to the other outside line of 50 the three-wire circuit. It is thus clear that a coil on each leg in multiple with a coil on the other leg is connected across one and the other side of the system respectively.

In Figs. 10 and 12 is shown a manner of 55 connecting parts of the secondary on different legs in multiple across one side of a three-wire system, which manner is the electrical equivalent of that shown in Fig. 8. This arrangement possesses the mechanical and

60 economical advantage, however, that the secondary is composed of only two coils, one on each leg. Leads A and B extend from intermediate points of these two coils and are connected by the lead L² with the neutral N of a three-wire system. The leads 65 A' and B' of the two coils are connected by the lead L' to the line W' of the three-wire system, and the leads A² and B² of the two coils are connected by the lead L³ to the line 70 W² of the three-wire system. By these 75 connections a part of the coil on one leg is connected in multiple with a part of the coil on the other leg across one side of the three-wire circuit, and the other part of the coil on the first leg is connected in multiple with the 80 other part of the coil on the other leg across the other side of the three-wire circuit. Thus the demagnetizing effect of a more heavily loaded secondary will act equally on both core-legs or along the entire length of the 85 core even though four separate coils are not provided, as in Fig. 8. It is preferable, however, that each of these secondary coils be wound throughout its length with a double conductor in order that all parts may be 90 in proximity to the coils of the primary, which would not be the case if each secondary coil were wound with a single conductor and the leads A or B were tapped midway into it. When each secondary coil is 95 thus wound with two conductors the arrangement is practically the same as that shown in Fig. 8, the only difference being that in the former case, as in Fig. 10, the 100 part of the winding on one leg is composed of a continuous conductor and is a single mechanical structure.

What I claim as new, and desire to secure by Letters Patent of the United States, is—

1. In a transformer, the combination with 105 a core constituting a single magnetic circuit, of a winding consisting of sets of coils, the sets being located on different parts of the core, the coils on the same part of the core being connected respectively in series with 110 coils on another part of the core and the sets of coils in series being joined in multiple, and a second winding in inductive relation with respect to the first winding.

2. In a transformer, the combination with 115 a core constituting a single magnetic circuit, of a winding consisting of multiply-connected sets of coils, each set consisting of an inner and an outer coil in series with each other.

3. The combination in a transformer, of a 120 core having a single magnetic circuit, a primary winding mounted thereon, and a secondary winding consisting of two sets of coils in multiple with each other, each of said sets being composed of two coils, one of said 125 coils being located on one leg of the core and the other coil located upon the other leg of said core.

4. In a transformer, the combination with a core constituting a single magnetic circuit, of a winding consisting of multiply-connected sets of coils located on different parts of the core, each set consisting of an inner coil on one part of the core in series with an outer coil on another part of the core.

In witness whereof I have hereunto set my hand this 11th day of December, 1901.

WALTER S. MOODY.
